DESIGN FOR A SETTEE OR SIMILAR ARTICLE

Emil Hauser, New York, N. Y.

Application March 13, 1937, Serial No. 68,158

Term of patent 7 years

To all whom it may concern:

Be it known that I, Emil Hauser, a citizen of the United States and resident of New York, in the county and State of New York, have invented a new, original, and ornamental Design for a Settee or Similar Article, of which the following is a specification, reference being had to the accompanying drawing, forming part thereof.

The drawing is a perspective view of a settee incorporating my new design.

The dominant feature of my design resides in the individual back panel units, and it will be understood that the panel units shown in dotted lines are to be considered as bearing the same design shown in the center panel.

I claim:

The ornamental design for a settee or similar article substantially as shown and described.

EMIL HAUSER.
